UNITED STATES PATENT OFFICE.

FRANK L. GORMLEY, OF BROOKLINE, MASSACHUSETTS, ASSIGNOR TO A. O. NORTON,
INC., OF BOSTON, MASSACHUSETTS, A CORPORATION OF MAINE.

HIGH-SPEED LIFTING-JACK.

1,376,869.

Specification of Letters Patent.

Patented May 3, 1921.

Application filed September 10, 1920. Serial No. 409,420.

To all whom it may concern:

Be it known that I, FRANK L. GORMLEY, a citizen of the United States of America, and a resident of Brookline, in the county of Norfolk and Commonwealth of Massachusetts, have invented certain new and useful Improvements in High-Speed Lifting-Jacks, of which the following is a specification.

10 This invention relates to high speed lifting jacks and particularly to that class of jacks known as self-run-down jacks adapted to be lowered under the weight of the load and in which the speed of lowering may be retarded by a suitable brake mechanism under the control of the operator.

15 The object of the present invention is the production of a self-run-down lifting jack in which the operating and braking mechanism are all positioned in the base of the jack.

20 The invention consists primarily in a revoluble lifting screw provided with a gear secured to the lower end thereof and a main operating mechanism for lifting the load co-25 acting with said gear and a holding and braking mechanism also coacting with said gear and adapted to be actuated only during the lowering operation.

25 The invention further consists in certain 30 novel features of construction and arrangement of parts which will be understood readily by reference to the description of the drawings and to the claims to be hereinafter given.

35 For the purpose of illustrating the invention, one preferred form thereof is illustrated in the drawings, this form having been found to give satisfactory and reliable results although it is to be understood that 40 the various instrumentalities of which the invention consists can be variously arranged and organized and the invention is not limited to the precise arrangement and organization of these instrumentalities as herein 45 shown and described, except as required by the scope of the appended claims.

Of the drawings:

Figure 1 represents a vertical section of a lifting jack embodying the principles of 50 the present invention.

Fig. 2 represents an elevation of the inner

side of the side plate carrying the retarding mechanisms, the driving shaft being shown in section.

Fig. 3 represents a horizontal section of 55 the same on line 3, 3, on Fig. 2.

Fig. 4 represents an elevation of the retarding and braking mechanisms, portions thereof being shown in section, and

Fig. 5 represents an elevation of a portion 60 of the jack showing the lever for actuating the brake mechanism.

Similar characters indicate like parts throughout the several figures of the drawings.

65 In the drawings, 10 is a base having extending upwardly therefrom a centrally disposed cylindrical projection 11 to which is threaded the lower end of a casing 12.

This casing 12 is provided with rectangular lateral flanges 13 and 14 preferably opposite each other as indicated in Fig. 1.

70 These flanged openings give access to the interior of the casing 12 and are normally closed by plates 15 and 16 respectively.

75 The upper end of casing 12 has a vertical cylindrical portion 17, the interior wall 18 at the upper end of which forms a bearing surface for a movable member or ram 19.

The upper end of the ram 19 has a serrated surface 20 adapted to contact with the load to be lifted and the lower end of said ram is provided with a nut 21 secured from turning therein by the members 22.

80 The nut 21 coacts with a revoluble screw 23 the pitch of the thread of which is such as to permit said screw to be turned when the nut 21 is forced downwardly under the load.

85 The lower end 23^x of the screw 23 has a bearing in a plate 24 resting in a recess in the projection 11, said plate 24 having in its upper face an annular track 25 for a plurality of balls or other anti-friction members 26.

90 These balls extend into an annular track 27 formed in the under side of a plate 28 surrounding the hub of a bevel gear 29 keyed to the lower end 23^x of the screw 23.

95 When the screw 23 is rotated by the gear 29, the revolution thereof will cause the nut 21 and ram 19 to move upwardly to lift the

load and when under the weight of the load the ram 19 and nut 21 is moved downwardly. This downward movement of the nut will cause the rotation of the screw 23.

- 5 The ram 19 is free to rotate when it is not supporting a load and its upper end is provided with a plurality of radial depressions 30 to receive the end of actuating members whereby the ram 19 may be quickly rotated 10 and thereby moved upwardly until the surface 20 comes into contact with the load to be lifted after which power may be applied to move the ram 19 further in an upward direction to lift the load.
- 15 The lifting mechanism is all mounted upon the side plate 15 and when said plate is removed from the flange 13, the entire lifting mechanism is removed therewith.

This lifting mechanism consists of a bevel 20 pinion 31 meshing with the bevel gear 29, said pinion 31 having keyed thereto a spur gear 32 and being provided with cylindrical axial-hubs 33 and 34.

The hub 33 is mounted in a bearing 35 in 25 the plate 15 and the hub 34 is mounted in a bearing in a bracket 35 secured to the inner face of the plate 15 in any well-known manner.

The gear 32 meshes with a pinion 36 on 30 the main operating shaft 37, said shaft being adapted to rotate in a bearing 38 in the plate 15 and a bearing 39 in a bracket 40 secured to the inner face of the plate 15 in any usual manner.

- 35 On the outer end of the shaft 37 is mounted a usual form of operating device 41 but as this operating device forms no part of the present invention, it is believed to be unnecessary to describe the same in detail.
- 40 By actuating the operating device 41 rotary movement will be imparted to the gears 36, 32, and 31 which rotary movement will be transmitted to the gear 29 and screw 23 and the lifting of the load will be 45 effected.

When the load is to be lowered under its own weight, the actuating device is placed in neutral position thus permitting the gears 29, 31, 32 and 36 to freely rotate.

50 The jack is provided with a retarding mechanism which is entirely supported on the removable side plate 16 and which may be removed therewith.

The retarding mechanism is connected to 55 the gear 29 of the screw 23 by means of a bevel pinion 42 having a hub 43 revolvably mounted in a gland 44 fixedly secured in the plate 16.

Keyed to the hub 43 is a ratchet wheel 45, 60 the teeth of which, during the lowering operation, are adapted to be engaged by pawls 46 carried by a spur gear 47 freely rotatable about the axis of the gland 43.

The teeth of gear 47 mesh with those of

a pinion 48 revolvably mounted in bearings 65 49, 49 and having threaded or otherwise secured thereto a spur gear 50 which meshes with a worm 51.

The thread of the worm 51 is of such a pitch that the worm will be rotated by the 70 rotation of the gear 50.

The worm 51 is formed upon a shaft 52 revolvable in bearings 53 in a bracket 54 secured to the inner face of the plate 16.

Extending from one end of the shaft 52 75 is a reduced shank 55 to which is threaded or otherwise secured the gear 56, the teeth of which mesh with those of a pinion 57 secured to one end of a shaft 58 parallel with the worm shaft 52 and freely revolvble 80 in a bearing in the bracket 54.

The opposite end of the shaft 58 has secured thereto a gear 59, the teeth of which mesh with those of a pinion 60 freely revolvble 85 about a sleeve 61 threaded or otherwise secured to the reduced end 62 of the shaft 52.

The hub of the pinion 60 has secured thereto a brake wheel 63 which rotates at a speed considerably greater than the speed 90 of rotation of the worm 51.

As a consequence of the high speed of the brake wheel 63 as compared with the speed of rotation of the main screw 23, it is obvious that slight frictional contact with 95 the brake wheel 63 will effectually retard the rotation of the screw 23 and thereby control the lowering of the load.

Moreover, the extended train of reduction gearing between the screw 23 and the brake 100 wheel 63 is sufficient to retard materially by its inertia, the speed of descent of the movable member of the jack.

The bracket 54 has pivoted thereto at 64, the brake arms 65 which partially surround 105 the periphery of the brake wheel 63 and are normally held in contact therewith by the springs 66 interposed between fixed members and the free ends 67 of the brake arms 65.

Between the free ends 67 of the brake arms 65 is interposed a cam-member 68 having flat sides as shown in Fig. 4.

This member 68 is revolvble about the stud 69 and on its outer end has an actuating lever 70.

The movement of the lever 70 is limited in one direction by the pin 71 and in the other direction by the guard flange 72 formed upon the plate 16.

When the brake arms 65 are in contact with the wheel 63, as shown in Fig. 4, the load will be retained in raised position but when these arms are moved from contact with said wheel, the jack will run down 125 under the load.

The speed of this lowering may be controlled by the operator manipulating the

lever 70 and thereby regulating the degree of frictional contact between the brake wheel 63 and the arms 65.

By constructing the jacks in the manner shown and described with the operating parts all in the base, the top-heavy appearance of the usual lifting jacks is avoided and a jack produced having a greater degree of stability.

10 By providing the main screw with a lifting mechanism on one side thereof and a speed controlling mechanism diametrically opposite the lifting mechanism, a perfectly balanced jack is obtained.

15 It is believed that the operation and many advantages of the invention will be understood readily without further description.

Having thus described my invention, I claim—

20 1. In a lifting jack, the base; a standard superimposed thereon; a movable member therein; a nut in the lower end thereof; a lifting screw in said nut; a gear secured to the lower end of said lifting screw; two 25 pinions meshing with said gear; a lifting mechanism adapted to rotate one of said pinions; a brake mechanism and means controlling the operation of said brake mechanism adapted to be actuated by the other 30 pinion.

2. In a lifting jack, a base; a standard superimposed thereon; a movable member therein; a nut in the lower end thereof; a lifting screw in said nut; a gear secured to the lower end of said lifting screw; two pinions meshing with said gear; a lifting mechanism; means operable by said lifting mechanism adapted to rotate one of said pinions; a brake mechanism; and a one-way 35 40 driving connection between said brake mechanism and the other pinion whereby said brake mechanism will be placed in commission only during the lowering operation.

3. In a lifting jack, a base; a standard superimposed thereon; a movable member therein; a nut in the lower end thereof; a lifting screw in said nut; a plate in the base having a smooth cylindrical bearing for the lower end of said screw; a gear secured to the lower end of said lifting screw; two pinions meshing with said gear; a lifting mechanism; means operable by said lifting mechanism adapted to rotate one of said pinions; a brake mechanism and means controlling the operation of said brake mechanism adapted to be actuated by the other 50 55 pinion.

4. In a lifting jack, a base; a standard threaded to and extending upwardly therefrom; a vertically movable member in said standard; a nut in the lower end thereof; a lifting screw in said nut; a braking mechanism coacting with the lower end of said screw, and a lifting mechanism independent

of said braking mechanism also coacting 65 with the lower end of said screw.

5. In a lifting jack, a base; a standard secured thereto and extending upwardly therefrom; a vertically movable member in said standard freely revoluble in said standard when not surmounted by a load; a nut in the lower end thereof; a lifting screw in said nut; a braking mechanism coacting 70 75 with the lower end of said screw and a lifting mechanism independent of said braking mechanism also coacting with the lower end of said screw.

6. In a lifting jack, a base; a standard extending upwardly therefrom and having diametrically opposed lateral openings 80 therein; a movable member in said standard; a nut in the lower end thereof; a lifting screw in said nut; a gear secured to the lower end of said lifting screw; a removable plate for each lateral opening; a lifting 85 mechanism mounted on one plate including a pinion adapted to mesh with said gear; and a braking mechanism on the other plate including a pinion adapted to mesh with said gear. 90

7. In a lifting jack, a base; a standard extending upwardly therefrom having a lateral opening; a member movable vertically in said standard; a nut in the lower end thereof; a lifting screw in said nut; a bevel 95 gear secured to the lower end of said screw; a removable plate for said lateral opening; a bevel pinion rotatably mounted in said plate and adapted to mesh with said gear; a spur gear revoluble with said bevel pinion; and an operating mechanism also mounted on said plate and including a revoluble pinion meshing with said spur gear. 100

8. In a lifting jack, a base; a standard extending upwardly therefrom having a lateral opening; a member movable vertically in said standard; a nut in the lower end thereof; a lifting screw in said nut; a bevel gear secured to the lower end of said screw; a removable plate for said lateral opening; 110 a bevel pinion rotatably mounted in said plate and adapted to mesh with said gear; a braking mechanism mounted on said plate; means actuated by said bevel pinion for operating the braking mechanism only 115 during the lowering operation; and means independent of said braking mechanism actuating devices for rotating said screw gear.

9. In a lifting jack, a base; a standard extending upwardly therefrom having a lateral opening; a member movable vertically in said standard; a nut in the lower end thereof; a lifting screw in said nut; a bevel gear secured to the lower end of said screw; a removable plate for said lateral opening; 120 a bevel pinion rotatably mounted in said plate and adapted to mesh with said gear; a brake wheel mounted for rotation on said 125

plate; a driving gear for actuating said brake wheel; a one-way driving connection between said driving gear and bevel pinion; brake members coacting with said wheel; and means independent of said brake wheel actuating devices for rotating said screw gear.

10. In a lifting jack, a base; a standard extending upwardly therefrom having a lateral opening; a member movable vertically in said standard; a nut in the lower end thereof; a lifting screw in said nut; a bevel gear secured to the lower end of said screw; a removable plate for said lateral opening; 15 a bevel pinion rotatably mounted in said plate and adapted to mesh with said gear; a

brake wheel mounted for rotation on said plate; a driving gear for actuating said brake wheel; a ratchet wheel secured to and revoluble with said bevel pinion; a plurality of pawls carried by said spur gear and coacting with said ratchet wheel; brake members coacting with said wheel; and means independent of said brake wheel actuating devices for rotating said screw gear. 25

Signed by me at 746-7 Old South Bldg., Boston, Mass., this 1st day of September, 1920.
